The ornamental design for a dental band as shown and described.

DESCRIPTION

FIG. 1 is a perspective view of a dental band embodying the new design;

FIG. 2 is a front view thereof;

FIG. 3 is a top view thereof;

FIG. 4 is a bottom view thereof;

FIG. 5 is a left view thereof;

FIG. 6 is a right view thereof;

FIG. 7 is a perspective view embodying the new design;

FIG. 8 is a front view thereof;

FIG. 9 is a top view thereof;

FIG. 10 is a bottom view thereof;

FIG. 11 is a left view thereof; and,

FIG. 12 is a right view thereof.

FIGS. 1-12 show portions of the dental band in broken lines. The broken line portions form no part of the claimed design. Those dash-dot broken lines shown adjacent to a solid line form unclaimed boundaries of the claimed design.
